DESIGN FOR A COIL CORD FOR ELECTRIC CURRENT

Clarence P. Berolzheimer, Chicago Heights, Ill.

Application March 13, 1933, Serial No. 47,439

Term of patent 7 years

To all whom it may concern:

Be it known that I, CLARENCE P. BEROLZHEIMER, a citizen of the United States, residing at Chicago Heights, in the county of Cook and State of Illinois, have invented a new, original, and ornamental Design for a Coil Cord for Electric Current, of which the following is a specification, reference being had to the accompanying drawing, forming part thereof.

Fig. 1 is a side elevational view of the coil cord

for electric current showing my new design, a portion being broken away for convenience of illustration, and,

Fig. 2 is an enlarged view of a portion of the cord.

I claim:

The ornamental design for a coil cord for electric current, as shown.

CLARENCE P. BEROLZHEIMER.
